UNITED STATES PATENT OFFICE.

ALEXANDER NYMAN, OF EAST ORANGE, NEW JERSEY, ASSIGNOR TO DUBILIER CONDENSER CORPORATION, A CORPORATION OF DELAWARE.

VARIABLE CONDENSER.

Application filed May 24, 1924. Serial No. 715,628.

My invention pertains to improvements in electrical condensers; especially condensers designed for variation of capacity in actual operation.

5 An object of the invention is to provide a variable condenser that can be employed with all kinds of electrical apparatus; but is particularly adapted for signalling by radio; for example, in broadcasting or receiving by being adjusted to work with any wave length that is being used.

A further object of the invention is to provide a condenser in which the elements of conductive material are in part movable, 15 the movable elements being constituted of an easily controlled fluid that has the property of receiving and carrying a charge of electricity for the necessary period of time, the effective quantity of the fluid being capable of regulation to afford the capacity desired at any particular instant.

Other objects and advantages of this invention will be set forth in the following description, taken with the accompanying 25 drawings, and the novel features of the improved condenser will be defined in the appended claims; but I of course reserve the right to make changes, not necessarily illustrated but embraced within the scope and 30 spirit of the invention, as indicated by the broad and general meanings of the terms in which the appended claims are expressed.

On the drawings:

Figure 1 is a side view, somewhat diagrammatic, of a complete condenser according to my invention;

Figure 2 is a perspective view of one part of a casing to receive the electrically conductive fluid employed in the practice of my 40 invention;

Figure 3 shows in perspective another part of said casing;

Figure 4 is a top view of said casing, with part of the supply conduits shown in broken 45 lines;

Figure 5 is a cross section on line 5—5 of Figure 4;

Figure 6 is a front view of said casing, the supply conduits being in cross section;

50 Figure 7 is a front view of an insulating plate carrying elements of solid electrically conductive material to cooperate with the conductive fluid in the condenser;

Figure 8 is a side view of said plate;

Figure 9 is a top view thereof; and

Figure 10 is a vertical section showing the casing above mentioned and one of the plates presented in Figures 7, 8 and 9 beside it;

The same numerals identify the same parts throughout.

I can best describe the condenser herein presented by reference first to Figures 2, 3, 7 and 10. In Figures 7 and 10, 1 is a plate or sheet of insulation, such as mica, having 55 on one face a number of fixed, solid elements, in the form of parallel strips 2 of conducting material, arranged side by side, but separated from one another. To co-operate with such strips, I employ a number of movable 60 elements each consisting of an electrically conductive fluid which must be of such a character that it can be easily operated and impelled into proximity with a greater or less number of the strips 2. For the purpose 65 of this invention, I find mercury to be the most suitable, because it is not only a liquid at ordinary temperatures, but also metallic in its nature and, therefore, quite as conductive as the strips 2, which can be of 70 any convenient metal, such as tinfoil, or the like. These movable elements of mercury are indicated at *m* in Figure 10 and they are contained in a casing 3, comprising a number of guideways 4, each of which is in 75 proximity to one of the strips 2, and parallel therewith, being separated from the strips of the nearest plate by the material of which the sides or opposite faces of the casing is 80 made. The design of the condenser permits 85 the level of the mercury in the casing 3 to be varied, as by being raised or lowered, and of course, it is obvious that the higher 90 the level of the mercury in this casing or container, the greater the number of guide- 95 ways or ducts which will be filled by the mercury and therefore, the larger the number of metallic fluid elements *m* that will be disposed in the condenser in position to co-operate with the strips 2, and thus the ca- 100 pacity of the condenser can be varied.

Figure 1 indicates the manner in which the parts of the condenser are assembled. It illustrates the condenser as including a convenient number of structures or casings 3, 105 each in communication with a conduit 5 through which mercury is supplied; and with the total number of containers 3, plates

1, with strips 2, and other important parts of the condenser, clamped firmly between means comprising plates 6 at the two ends. The conduit 5 leads to a pumping device 7, 5 containing two chambers 8 and 9, separated by an operating member in the form of a piston or movable partition 10. The conduit 5 communicates with the chamber 8 on one side of the piston, and leading from the 10 chamber 9 on the opposite side of the piston is a similar conduit 11, which also communicates with the different container structures 3. The container structures 3 will be in suitable number and spaced apart, with as 15 many plates 1 bearing strips 2, as desired, between them. Each plate or body 1 with strips 2 thereon constitutes a separate unit and in the middle of the number of such units, between each two adjacent casings 3, 20 I insert a terminal member in the form of a metal plate or block 12. In Figure 1, I show five of such units between each of the terminal members 12, and the adjacent casings 3, and each group of units between one of the 25 terminal members 12, and any one of the adjacent casings 3, will constitute a section, the various units of which are in series; that is, each strip of one plate will be in series with the nearest or corresponding strips of 30 the adjacent plates. From the member 12 may extend connectors 13, leading to an electric conductor 14, forming one extremity of the circuit in which the condenser is to be employed, and the other extremity of said 35 circuit may be joined to a pipe 5. Hence, as Figure 1 indicates, the strips of each unit are in series with the corresponding strips of the other units of each section; while the various sections themselves are united in parallel.

40 I shall now describe more fully the casings 3, which are illustrated in perspective in Figure 2. Each of these casings may have one side or face consisting of a plate of insulation 15 carrying at the upper and lower edges plates or bars 16 and 17. Between the 45 two bars are ribs 18 spaced one from another and from the bars 16 and 17, to provide the channels or guideways 4 for the mercury; the bars 16 and 17, and the ribs 18 all being 50 fixed to one face which is the inner face of the insulating plate 15. The casing is completed by fitting to the plate over the bars and ribs thereon, a cover 19 having ends 55 which will overlap the ends of the plate 15, this cover being best shown in Figure 3. As Figure 2 plainly indicates, the bar 16 at the top of the plate 15 is flush at one end with the end of the plate 15, but terminate 60 short of the opposite end; and the bar 17 has one extremity flush with this opposite end of the plate, while the other end of this bar terminates short of the first end of the plate 15. All the ribs 18 are shorter than 65 the length of the plate 15, so that when the

cover 19 is fitted upon the plate 15, there will be vertical guideways or header spaces at each end of the ducts or guideways 4, and communicating with the opposite ends thereof. These header spaces are indicated by the numerals 21, and the lower end of the header space 21, which extends downward past the bar 17, will be arranged so as to lead to the mercury supply pipe 5; while the upper end of the other header space 21 which extends 75 past the bar 16 will be put into communication with the pipe 11. To connect the pipes 5 and 11 to these vertical guideways or header spaces, I may employ cap plates 22 fitting over the tops and bottoms of the casings adjacent the outer ends of these header spaces and leading to couplings 23, to enable the conduits 5 and 11 to be joined to these spaces 21.

80 Of course, the plate 15, the cover 19 and the cap plates 22 will be made leakproof in any feasible manner which need not here be described. The header spaces 21 of the containers 3 are illustrated as leading out through the upper corners to the conduit 11, 85 on the side toward the observer, with reference to Figure 1, and the header spaces on the opposite sides of these casings are indicated as leading out through the lower corners of the casings on the side away from the 90 observer, with reference to Figure 1, to the conduit 5. For this purpose, the conduit 5 may have a bend 24 therein leading across the front of the condenser as indicated in Figures 1 and 4. Preferably, the sheets 1 95 having the strips of foil 2 thereon carry these foils on only one face thereof; the opposite faces are placed against the terminal members 12 and when each section is made up, the units are so disposed that each sheet will 100 present the foil strips thereon to the back or uncovered face of the adjacent sheet, and the sheets being closest to the casings 3 will have the strips 2 thereon pressed directly against the outside surfaces of these casings.

105 The mercury will fill the chamber 8, and the conduit 5 and that portion of the mercury which is contained at any particular time in any one of the casings 3 will be the effective quantity of mercury in operation, and will constitute a terminal member in the same way as the plates 12. In the chamber 9, and the conduit 11, I use some insulating substance such as oil, and the oil and the mercury will be in sufficient 115 volume to fill the chambers 8 and 9, the conduits 5 and 11, and the spaces 4 and 21, so that in the casings the lower level of the oil 120 will always meet the upper level of the mercury. Hence, by moving the piston 10, the 125 relative quantity of oil and mercury in any one of the container structures 3 can be varied, and the effective quantity of the mercury thus regulated.

130 If the piston is pushed down, enough mer-

cury can be caused to flow into each of the casings 3 to fill every one of the guideways 4, and thus provide a mercury element *m* opposite each one of the tiers of strips 2 carried by the different dielectric sheets between the casings and the members 12. The greater the number of the spaces 4 filled with mercury, the greater will be the capacity, and the smaller the number of 10 such spaces filled with mercury, the less will be the capacity of the condenser.

The device 7 may be a pump, with a reciprocable piston in it, or it may be made like a bellows or accordion, with the walls 15 thereof fluted or corrugated, so that each portion above and below the partition 10 can be stretched or compressed to expand or contract either chamber 8 or 9. If made as shown, it may have a pair of disks 25 at 20 one end, held together by rivets to secure the adjacent edges of the bellows-like body between them, the disks 25 having an opening to receive the adjacent end of the conduit 5. At the middle, the partition or piston 10 may comprise similar disks 26, riveted together and secured to the sides, these 25 disks 26 also carrying a bearing 27 having an opening 28 for one end of an operating rod 29. At the upper end, the adjacent 30 edges of the body of the pumping device may be secured between a pair of disks 25, similar to those at the bottom, and these disks besides being perforated to receive the end of the conduit 11, may carry a threaded bearing 30 through which the rod 29 may pass, carrying on its outer end an operating knob 31. The inner end of this rod is smooth, to project loosely through the aperture 28 in the bearing 27, and a pin 32 40 may be driven through the inner end below the bearing 27, to cause the rod to engage the bearing to permit rotation of the rod in it. Hence, when the rod is turned, the partition or piston 10 is actuated up or down. 45 Of course, this device can be made in sections 33 and 34 and some material that can be fluted or corrugated to permit it to be collapsed or expanded, the opposite or remote edges of the section being gripped together by the disks 25, and the adjacent edges being secured between the disks 26 of the piston 10. At 35, I indicate diagrammatically the opposite terminal of the circuit attached to the conduit 5.

From the foregoing description, it will be seen that the capacity of the condenser can be varied in a positive and certain manner and the structure and design in such that there is no likelihood of any of the parts 60 being displaced or the function of the condenser becoming impaired in practice. Only the mercury and the members 12 are directly connected to the extremities of the circuit in which the condenser is to work, the strips 2 being isolated. This arrange-

ment of sections in multiple and units having strips which are in series, gives a condenser with low internal resistance, so that little heating occurs when the condenser is in use; while the plates 1 or the sides of the 70 casings can be made as thick as is necessary for high potential, and the dielectric sheets 1 can have spaces at their opposite sides adjacent the ends of the strips 2 and at the top and bottom of sufficient width to give 75 a large creepage distance between the units. The blocks 6 are forced against the extremities of the assembled condenser with sufficient tightness to hold the strips 2, the sheets 1, and the exteriors of the casings 3 80 in firm engagement, and thus maintain most efficient contact between the conductive elements of the condenser, and the dielectric separating them.

It is understood, of course, that the conductive strips 2 may be made as thick or as thin as may be desired; and the container structure, the parts of which are shown in perspective in Figures 2 and 3, appears as if seen from the left of Figure 1. 85

The reason for dividing the insulation 2 into strips is to enable the capacity to be increased or reduced step by step, without concentration at any one point. If the insulation 2 were in the form of sheets the capacity would be concentrated along the lower edge of the sheets whenever the mercury level is low enough to fill only the first or second duct 4 at the bottom, and thus too much potential at one part of the condenser 95 would result.

The plates 1, strips 2, and the plates 15 and 19, with the bars 16 and 17 and ribs 18 are really shown with thickness out of proportion in the drawings, merely for the sake 105 of clearness.

Plates 15 and 19 may be of mica, and so may the bars 16 and 17. In this case the ends of the plate 19 will not have bent ends 20, but mica strips vertically placed between the plates 15 and 19 will close the spaces between the vertical sides of the two plates 15 and 19, thus closing the sides of the casing 3 and the outer sides of header spaces 21.

Having described my invention, what I believe to be new and desire to secure and protect by Letters Patent of the United States is:—

1. An electrical condenser including a plurality of elements of conductive material, all of said elements being substantially in the same plane, a structure having guideways adjacent said elements and likewise in substantially a single plane to receive a fluid conductive substance to cooperate with said elements, and means for causing movement of said substance in said guideways. 120

2. An electrical condenser including a plate of insulation, strips of conductive material arranged side by side on said plate, 125

and a structure having guideways adjacent said strips adapted to receive a conductive fluid to cooperate with said strips.

3. An electrical condenser including units, 5 each unit comprising a body of insulation with strips of conductive material arranged side by side on one face only of said body, so that when such a unit is combined with a similar unit with its opposite face presented to the conductive strips of said similar unit, said body will separate the conductive strips of the two units.

4. An electrical condenser including units, 15 each of said units comprising a body having strips of conductive material side by side on one face only, said strips being parallel with one another, each of said units capable of being combined with a similar unit, so that its opposite face is presented to the strips on 20 said similar unit, with the strips of each unit overlying the strips of the adjacent unit, but being separated by said body therefrom.

5. An electrical condenser including terminal members for connection with electric 25 conductors and isolated intermediate units, one of said members having the form of a casing to receive an electrically conductive fluid, the level of which is variable in said casing, some of said members extending between the intermediate units.

6. An electrical condenser including terminal members and intermediate units, said units comprising separated strips of conductive material, one of said members comprising a container having guideways adjacent said strips adapted to receive an electrically conductive fluid.

7. An electrical condenser including sections having isolated conductive elements 40 and terminal members for the sections to enable them to be connected to an electrical circuit, one of said members for each section being of solid material and the other comprising a structure to receive an electrically 45 conductive fluid, the quantity of which is variable, some of said terminal members extending between said sections.

8. An electrical condenser including solid 50 elements of electrically conductive material, a container having guideways adjacent said elements to receive an electrically conductive fluid, a pumping device including an operating member, and conduits between said device and communicating with opposite ends 55 of the guideways and opposite ends of the

pumping device, to enable said device to impel a fluid into one end of said guideways and a fluid into the opposite end of the guideways, one of said fluids being electrically conductive to cooperate with said elements. 60

9. An electrical condenser comprising strips of electrically conductive material arranged side by side, a plate of insulation to which said strips are secured, a container 65 having guideways extending adjacent said strips, and spaces connecting opposite ends of the guideways, a pumping device having a pair of chambers separated by a piston, a conduit for each chamber to connect one 70 chamber to one of said spaces and the other chamber to the remaining space, a quantity of fluid in one compartment to be forced into said guideways from the other of said spaces and a quantity of fluid in the other 75 compartment to be forced into said guideway from the other of said spaces, one of said fluids being electrically conductive, said fluids being in sufficient volume to fill the 80 chambers, the conduits and the guideways and spaces, and make contact with each other, whereby movement of the piston will vary the relative quantities of the two fluids in the container.

10. An electrical condenser comprising 85 strips of electrically conductive material arranged side by side, a plate of insulation to which said strips are secured, a container having guideways extending adjacent said strips, and spaces connecting opposite ends 90 of the guideways, a pumping device having a pair of chambers separated by a piston, a conduit for each chamber to connect one chamber to one of said spaces at the top 95 thereof, and the other chamber to the remaining space at the bottom thereof, a quantity of fluid in one compartment to be forced into said guideways through one of the spaces, and a quantity of fluid in the other compartment to be forced into said 100 guideways through the other space, one of said fluids being electrically conductive, said fluids being in sufficient volume to fill the chambers, the conduits and the guideways and spaces, and make contact with each other, whereby movement of the piston will 105 vary the relative quantities of the two fluids in the container.

In testimony whereof I affix my signature.
ALEXANDER NYMAN.
